F. HARDISTY,
ELECTRIC CLOCK.
APPLICATION FILED DEC. 17, 1914.

Patented Dec. 14, 1915.

2 SHEETS—SHEET 2.

UNITED STATES PATENT OFFICE.

FRANK HARDISTY, OF FRANKFORT, INDIANA, ASSIGNOR OF ONE-HALF TO CYRENIUS B. WILLIAMS, OF FRANKFORT, INDIANA.

ELECTRIC CLOCK.

1,164,511.

Specification of Letters Patent. Patented Dec. 14, 1915.

Application filed December 17, 1914. Serial No. 877,742.

To all whom it may concern:

Be it known that I, FRANK HARDISTY, a citizen of the United States, and a resident of Frankfort, in the county of Clinton and 5 State of Indiana, have made certain new and useful Improvements in Electric Clocks, of which the following is a specification.

My invention relates to improvements in electrically driven clocks and it consists in 10 the combinations, constructions, and arrangements herein described and claimed.

An object of my invention is to provide a clock which is run by a small amount of current and which therefore consumes very 15 little energy.

A further object of my invention is to provide a device of the type described having a novel form of actuating mechanism in which the pendulum is given an impulse 20 periodically, this impulse consuming very little current in that the movement of the pendulum breaks an electric-circuit immediately after the impulse, thereby economizing current.

25 A further object of my invention is to provide a novel form of striking mechanism which is also actuated electrically.

Other objects and advantages will appear in the following specification and the novel 30 features of the device will be particularly pointed out in the appended claims.

My invention is illustrated in the accompanying drawings forming part of this application in which—

35 Figure 1 is a face view of the actuating mechanism, Fig. 2 is a side view, Fig. 3 is a face view of the "hour" wheel, Fig. 4 is a face view of the "minute" wheel, and Fig. 5 is a face view of the "second" wheel.

40 In carrying out my invention I provide a support 1 to which is secured a laterally extending arm 2 having a V-shaped groove 2^a arranged to support a knife edge 3 carried by a ring 4^x which forms part of a yoke 4, the ends of the yoke being bent at right angles, as shown at 5 and constituting armatures for the magnets 6 which are supported by the arm 2, as shown in Fig. 2. The lower portion of the yoke has a downwardly extending rod 7 to which a pendulum bob 8 is adjustably attached. The pendulum rod 7 bears a pin or arm 9 upon which is pivotally mounted a wedge-shaped member 10.

Carried by the support 1 is a laterally extending arm 11 to which is secured the end of a spring contact 12. This contact bears a block 13 having a notch 14 in its top. The block 13 has a threaded extension 15 upon which a milled nut 16 may be screwed so as 60 to hold the block securely to the spring. The support 1 also bears a bracket 17 carrying the contact screw 18 and an adjusting screw 19 which is insulated from the contact screw 18 by an insulating plate 20. 65

A battery B is connected with the contact screw 18 on one side and on the other side by means of a conductor 21 to one of the magnets 6, these magnets being connected together by means of a conductor 22, 70 the other magnet 6 being connected with the spring contact 12 by means of a conductor 23 (see Fig. 1).

Mounted rigidly on the end of the arm 2 is a shaft 24 and arranged to revolve on the shaft is a sleeve 25 to which is rigidly secured a "second" wheel 26 and at its outer end a "second" hand 27. The "minute" wheel 28 is mounted on a sleeve 29 exterior of the sleeve 25 and bearing at its end the "minute" hand 30, while an "hour" wheel 31 is mounted on a sleeve 32 and bears at its end an "hour" hand 33. The wheel 26 bears preferably sixty teeth 26^t and it will be noted in Fig. 1 that this wheel has an extra deep slot 26^s between two of the teeth. The "second" wheel has a series of raised contacts 26^y arranged in spiral shape, as shown in Fig. 5. The "minute" wheel 28 is also preferably provided with sixty teeth and has five extra deep slots 28^x at equidistant points. It is provided on both sides with a series of twelve brush contacts 28^y corresponding to the contacts 26^y on the "second" wheel. The hour wheel 31 has also preferably sixty teeth and is provided on the side facing the minute wheel with contacts 31^y, these contacts varying in length, the lengths of the contacts being from one to twelve and the contacts themselves extending radially from the center of the wheel. 90 95

Secured to the end of the arm 2 is a laterally extending arm 34 which has a pawl 35 normally held by a spring 36 against the teeth 26^t of the wheel 26. An arm 37^x is rigidly connected with the central portion of the yoke 4 and pivotally connected at 37 to the arm is a pawl 38 having a laterally ex-

tending end 39 which is arranged to engage the teeth of the various wheels. As will be seen from Fig. 2 the pawl 39 has a portion 39^a which engages the teeth of the wheel 26, 5 but when the slot 26^x comes under the portion 39^a the pawl 38 can swing farther toward the center of the wheels under the action of the spring 40 so that the portion 39^b (see Fig. 2) will now engage the teeth of the 10 minute wheel 28. When one of the slots 28^x is engaged by the portion 39^b of the pawl this will permit the portion 39^c of the pawl to engage a tooth of the hour wheel.

In Fig. 2, I have shown a battery B' which 15 is connected by a conductor 41 with a brush 42 which is in engagement with the "second" wheel 26. The wheel 31 has a similar brush 43 which remains in contact with the wheel during the rotation thereof and is in electrical connection with the magnet 44 of a bell 45 mounted on the support 1, by means of a conductor 46. The magnet 44 is in turn connected by a conductor 47 with the battery B'. The wheels 26, 28 and 31 are insulated from each other and from the frame by insulating rings such as those shown at 26^z, 28^z and 31^z respectively, so that any current passing from the battery must flow by way of the conductors 26^y, 28^y and 31^y respectively. 30

From the foregoing description of the various parts of the device the operation thereof may be readily understood.

The pendulum bob 8 is adjusted to such a 35 length that the period of vibration is one second. Consider now Fig. 1 with the pendulum in the left hand dotted line position X and about to swing toward the right. The member 10 is free to swing on the pivot 40 9 so that it normally maintains a vertical position. This member will catch in the V-shaped notch 14 during the forward stroke, so that when the pendulum reaches its extreme passage at the right, as shown at Y, 45 and starts to return the member 10 will force the spring 12 downwardly, thus making contact at 18. Current will now flow from the battery B through 21, 6, 22, 6, 23, 12, 18 and battery. The armatures 5 are out of the 50 central position and there will thus be given a momentary impulse to these armatures to return to the central position. This will give an impulse to the pendulum thus keeping up the swing of the latter. At each 55 double swing of the pendulum the pawl 38 will move the "second" wheel forward one tooth, but when the wheel has made one revolution the end 39 will enter the slot 26^x, thereby bringing the portion 39^b into engagement with a tooth on the minute wheel, 60 thus turning the minute wheel. At every twelfth tooth on the minute wheel is a slot 28^x, as stated before, which permits the portion 39^c to move the hour wheel one tooth. The hour wheel is thus moved every twelve

minutes, but since there are sixty teeth on the hour wheel it will take twelve times sixty or seven hundred and twenty minutes, *i. e.*, twelve hours for the hour wheel to make one revolution.

Consider now the means for causing the audible indication of the hours.

The wheels 26, 28 and 31 are placed on their respective spindles in such a manner that the contact on the hour wheel for striking twelve, the row of contacts 28^y on the minute wheel, and the contact 26^y nearest the center of the wheel 26 are in registration at twelve o'clock. If now the pendulum is set going the "second" wheel will begin to 80 revolve and as the spiral row of contacts passes the brushes 28^y the bell 45 will receive current for ringing the same as each contact 26^y passes its corresponding brush on the wheel 28, each individual brush of the 85 wheel 28 being insulated from the other brushes, as shown in Fig. 4, the corresponding brushes on opposite sides of the wheel 28 being connected with each other. Approximately one hour will lapse after striking 90 twelve before the outer contact 26^y on the wheel 26, the outer brush 28^y on the wheel 28 and the smallest contact 31^y on the wheel 31 will again register. This will cause the 95 clock to sound the hour one. Similarly the hours two, three, four, etc., are sounded successively. Since the striking of the clock is caused by contacts which are momentarily made, very little current is required to maintain the striking feature.

It will thus be seen that I have provided a device for operating the clock which requires a very small amount of electrical energy. In fact the amount is so small that it can hardly be registered on a meter. The 105 device is simple in construction yet positive in operation. The accuracy of the clock, as in any clock, depends upon the correct adjustment of the pendulum bob, but this is readily accomplished and when 110 once adjusted the clock is not liable to get out of order because there are no springs to break. Furthermore there are no small bearings which must be well oiled and which tend to clog up, thereby 115 retarding the movement and either making the timing mechanism inaccurate or resulting in the stopping of the clock altogether. The fact that the clock contains but little mechanism renders the device cheap to 120 manufacture without in the least detracting from its reliability as a time piece.

I claim:—

1. In an electric clock, a "second" wheel, a minute wheel, an hour wheel, said wheels being arranged parallel to one another for rotation on a common axis, means for driving said wheels, a bell, and a magnetic circuit for said bell, said circuit including contacts on each of said wheels arranged to be 130

brought into registration by the rotation of the wheels and to close the circuit to cause the sounding of the bell.

2. In an electric clock, a "second" wheel, a minute wheel, an hour wheel, said wheels being disposed in parallel relation for rotation about a common axis, means for rotating said wheels, said "second" wheel being provided with a spiral row of contacts conforming to the hours of the day, said minute wheel being provided with a series of brushes conforming in number to the contacts on the "second" wheel, said brushes being arranged to extend beyond the face of the minute wheel on each side thereof and to engage the contacts on the "second" wheel successively, said hour wheel being provided with a series of raised contacts of different lengths corresponding to the hours of the day and adapted to be engaged by the brushes on one side of the minute wheel.
3. In an electric clock, a "second" wheel, a minute wheel, an hour wheel, said wheels being disposed in parallel relation for rotation about a common axis, means for rotating said wheels, said "second" wheel being

provided with a spiral row of contacts conforming to the hours of the day, said minute wheel being provided with a series of brushes conforming in number to the contacts on the "second" wheel, said brushes being arranged to extend beyond the face of the minute wheel on each side thereof and to engage the contacts on the "second" wheel successively, said hour wheel being provided with a series of raised contacts of different lengths corresponding to the hours of the day and adapted to be engaged by the brushes on one side of the minute wheel, an electro-magnetic sounding device, a battery, a brush connected with the battery on one side and being in electrical connection with said "second" wheel, a second brush having connection with said electro-magnetic device and being in constant electrical connection with said hour wheel, and electrical connections between said battery and said electro-magnetic device.

FRANK HARDISTY.
